UNITED STATES PATENT OFFICE.

SPENCER HEATH, OF BALTIMORE, MARYLAND.

VARIABLE-PITCH PROPELLER.

Application filed February 3, 1920, Serial No. 356,040. Renewed February 25, 1925.

To all whom it may concern:

Be it known that I, SPENCER HEATH, a citizen of the United States, residing at Baltimore, in the county of Baltimore and 5 State of Maryland, have invented certain new and useful Improvements in Variable-Pitch Propellers, of which the following is a specification.

This invention relates to screw propellers, 10 and more particularly to aircraft propellers of that type in which the blades are capable of simultaneous adjustment about their several longitudinal axes in such a manner that the pitch of the blades can be 15 varied at will or their action entirely reversed to any desired degree, all during continuous operation of the propeller.

The present invention is of a similar nature 20 to that covered by my prior copending application Serial No. 308,112, filed July 2, 1919, and its objects are generally the same. Among the features which it comprises, in common with such prior invention are, 25 that the blades are adjusted by engine power delivered to the propeller, manual or bodily force being required only for connecting and disconnecting the operating power; and that there are no operative connections, such as clutch collars, running 30 bearings, or the like, normally in engagement, such connections being established only momentarily during changes in adjustment of the blades.

Among the specific objects of the present 35 invention, as distinguished from my said prior application, are to eliminate the use of sprocket chains, to provide a better bearing for each propeller blade, to improve the construction of the worm gearing employed, and to devise a novel and more effective 40 control mechanism.

With the above and other objects in view the invention consists in the construction, 45 arrangement and combination of parts hereinafter described and claimed, and shown in the accompanying drawings, in which:—

Fig. 1 is an end elevation, half in section showing my improved propeller hub, with the blade shanks therein;

Fig. 2 is a similar view half in section and half in side elevation;

Fig. 3 is a section on the line X—X of Fig. 1, looking towards the right;

Fig. 4 is a section on the line X—X of Fig. 1, looking towards the left;

Fig. 5 is a fragmentary plan view of my controlling mechanism and associated parts;

Fig. 6 is a sectional elevation thereof, the section being taken substantially on the line 6—6 of Fig. 5, and 60

Fig. 7 is a sectional elevation, substantially on the line 7—7 of Fig. 5.

Referring to the drawings in detail, 1 designates in general my improved propeller hub, which as shown comprises a pair of 65 oppositely disposed tubular sockets, in which the blade shanks are mounted. The hub has a central body portion 2, which fits over the tapered end 3 of the engine shaft and is secured thereon by means of nuts 3^a. 70

The construction of each blade and controlling mechanism is the same, and, therefore, the description of one will suffice for both.

5 designates the blade shank which is secured in a ferrule 6 by means of an annular wedge 7. This ferrule is rotatably held within the hub socket and is secured in position by means of a flange ring 8, between which and the ferrule 6 is placed a thrust bearing 9 preferably of the anti-friction type. The inner end of the ferrule is formed with outwardly flaring walls which fit snugly within the hub socket, as indicated at 6^b, thus forming a bearing affording lateral support, and between this bearing and the anti-friction thrust bearing, the ferrule is cut away as indicated at 6^a, so as to provide a clearance between itself and the walls of the socket. This arrangement gives rise 90 to a structure which has great stability and at the same time freedom of movement.

Secured within the inner end of the ferrule 6 is an internal annular gear 10, and with this gear are arranged to mesh a pair 95 of pinions 11 positioned as shown in Fig. 3. Each pinion is rigidly mounted on a shaft 12, journaled in suitable bearings in a frame 13 secured in the hub socket as by means of screws 14.

Also mounted on the shafts 12 are a pair of worm wheels 15 as clearly shown in Fig. 4, and these worm wheels mesh with worms 16 formed on a transverse shaft 17 journaled as at 18 in the frame 13 and carrying at its outer end a gear wheel 19. It will be observed that the two worms 16 are of reverse pitch and that the worm wheels 15 are disposed on opposite sides of the shaft 17. The result of this construction is that when the 110

shaft 17 is rotated the worm wheels 15 and pinions 11 are both driven in such a direction as to co-operate in turning the annular gear 10, and with it the blade shank 5 about its axis.

The gear 19 meshes with a gear 20 rigidly secured to a large gear wheel 21 journaled on a stud shaft 21^a secured to the hub socket.

Freely journaled on an extension 4 of the hub is a sleeve 24 carrying a gear 23, and freely journaled on this sleeve is a second sleeve 30 carrying a gear 22. The gear 22 is in constant mesh with the gear wheel 21, and an idler pinion 25 journaled on a bracket 15 26 engages the gear 23 and gear wheel 21, thereby constantly connecting the same.

From the above it will be understood that there is a gear wheel 21 and associated parts for each blade of the propeller, and that all 20 of these gear wheels 21, as well as pinions 25 mesh with the two gears 22 and 23 as described.

Secured to the sleeve 24 is a brake wheel 27 and secured to the sleeve 30 is a brake wheel 29, these wheels being held in assembled relation by a ring 28 and separated by a spacing ring 28^a. 31 designates the casing or frame of the engine, which drives the propeller. Secured to this frame by means 30 of brackets 32 is a circular housing 33 concentric with and enclosing the brake wheels 27 and 29. This housing preferably has an annular flange 34 positioned between the brake wheels and an annular flange 35 in front of brake wheel 29.

Rigidly carried by housing 33 is an up-standing bifurcated bracket 36 between the legs of which rests a controlling lever 37. This lever is not pivoted to the bracket 36, 40 but can slide freely relative thereto. The inner end of this lever 37 is somewhat T-shaped, having a transversely extending portion 38 as clearly shown in Fig. 6, and in 45 the ends thereof are set a pair of pivot pins 39 and 40. A brake band 41 surrounds the brake wheel 29 and is secured at its free end to the pivot pin 40, the other end of such band being fixed to the housing as indicated at 42. A similar band 43 surrounds the 50 brake wheel 27 and has its free end secured to the pivot pin 39.

Secured to the bracket 36 is a pair of guide plates 44, 45, provided with curved slots 46, 47, through which the pivot pins 39 55 and 40 extend and in which they can freely slide. The slots in which the pin 39 works are formed around the pin 40 as a center and the slots in which the pin 40 works are formed around the pin 39 as a center. Thus 60 the lever 37 is capable of pivotal movement about either of the pins 39 or 40. When moved about the pin 39, it is obvious that the band 41 will be tightened, and when swung about the pin 40, the band 43 will be 65 tightened.

This arrangement produces a very effective braking action and obviates all binding or clamping of the parts.

The operation of the mechanism according to the present invention, is the same as 70 that of my above mentioned prior application. The tightening of the brake bands on the brake wheel 27 causes the gear wheels 21 to be driven by means of the gear 23 and the pinions 25, thus actuating the shafts 17 75 and turning the blades in one direction, while tightening of the brake bands on the brake wheel 29 causes the gear wheels 21 to be driven directly by means of gear 22, thus turning the blades in the opposite direction. 80 In the present invention, however, I have eliminated the use of chain and sprocket gearing and have provided a transmission consisting entirely of supporting gears 85 constantly in mesh. This produces a construction which will stand up better at high speeds, is more compact and less liable to derangement.

While in my former application, I have shown a single worm with crossed threads, 90 I achieve the same result in the present invention by means of two separate worms, arranged as shown in Fig. 4 and this latter construction I regard as mechanically preferable.

What I claim is:

1. A propeller comprising a hub having a socket, a blade having a shank rotatable about its own axis in said socket, and means for so rotating said blade in either direction, 100 said means comprising a pair of independent toothed gears rotatable about the same axis, a gear wheel carried by said hub and meshing with one of said gears, an idler pinion meshing with said gear wheel and with the 105 other of said gears, a shaft extending transversely of said hub, gear mechanism operatively connecting said shaft and said last named gear wheel whereby rotation of the latter will cause rotation of the shaft, and means mounted within said hub and operated from said shaft for rotating said blade.

2. A propeller comprising a hub having a socket, a blade having a shank rotatable about its own axis in said socket, and means for so rotating said blade shank in either direction, said means comprising a pair of independent toothed gears journaled on said hub, co-axially thereof, and a pair of rigidly united gear wheels also rotatably supported on said hub, eccentrically thereof, one of said rigidly united wheels being operatively connected with said blade shank, the other of said wheels being in mesh with one of said toothed gears, and an idler pinion meshing with said last mentioned wheel and the other of said toothed gears.

3. A propeller comprising a hub having a tubular socket of uniform diameter throughout, a ferrule rotatably mounted in such 130

- socket, a blade secured in said ferrule, a thrust bearing for the ferrule at the outer end of the socket, and the side walls of the inner end of said ferrule being flared outwardly and engaging the interior cylindrical surface of said socket to form a laterally supporting bearing, the ferrule being of reduced external diameter between said two bearings so as to afford a clearance between itself and the socket, an annular gear secured to the inner wall of said flared portion of said ferrule, and means for rotating said gear and ferrule.
4. In a propeller, the combination with a hub, of a blade mounted therein for rotation on its own axis, and gearing for rotating said blade, said gearing including a pair of separate rigidly connected worms, mounted on the same axis, a pair of oppositely disposed worm wheels meshing therewith, and means operated by said worm wheels for applying a turning force to said blade at points on opposite sides of its axis of rotation.
5. In a propeller, the combination with a hub, of a blade mounted therein for rotation on its own axis, and gearing for rotating said blade, said gearing comprising a pair of separate, reversely arranged worms mounted on the same shaft, a pair of worm wheels meshing therewith, and disposed on opposite sides of such shaft, and means operated by said worm wheels for applying a turning force to said blade at a plurality of points.
- 35 6. A propeller comprising a hub having two oppositely directed sockets, a blade mounted in each of said sockets for rotation about its own axis, and means for simultaneously rotating said blades, said means comprising a pair of independent toothed gears rotatable about the same axis, two gear wheels carried by said hub and arranged on opposite sides of said toothed gears, both of said gear wheels being in mesh with one of said gears, each of said gear wheels having an idler pinion meshing therewith and with the other of said gears, each of said gear wheels also having a second gear wheel rigid therewith, two shafts extending transversely of said hub, one for each blade, each of said shafts carrying a gear wheel which meshes with one of said second gear wheels, whereby said shafts are rotated, and means operated by rotation of each shaft for rotating its respective blade.
9. A propeller comprising a hub having a socket, a blade having a shank rotatable about its own axis in said socket, and means for so rotating said blade, said means comprising a pair of independent toothed gears rotatable about the same axis, a gear wheel carried by said hub and meshing with one of said gears, an idler pinion meshing with said gear wheel and with the other of said gears, a second gear wheel rigid with said first named gear wheel, a shaft extending diametrically through said hub and transversely of the axis of said blade, said shaft having a gear wheel meshing with said second gear wheel, and gear mechanism arranged within said hub and operated by rotation of said shaft for rotating said blade.
10. In a propeller, the combination with a hub, of a blade mounted therein for rotation on its own axis, and gearing for rotating said blade, said gearing comprising a gear secured to said blade, pinions engaging said gear on the opposite sides of the axis of rotation of the blade, a worm shaft extending transversely of said hub, a pair of separate spaced worms rigid with said shaft, a pair of worm wheels disposed on opposite sides of said shaft and engaging said worms, each of said worm wheels being connected with one of said pinions, and means for rotating said shaft.
11. A propeller comprising a hub having a socket, a blade having a shank rotatable about its own axis in said socket, and means for so rotating said blade shank in either

- direction, said means comprising a pair of independent toothed gears journaled on said hub, a gear wheel meshing with one of said gears, an idler pinion meshing with said gear wheel and the other of said gears, a worm shaft extending diametrically through said hub and operatively connected to said gear wheel, a pair of worms spaced apart on said shaft and rigidly secured thereto, a pair of oppositely disposed worm wheels meshing therewith, and means operated by said worm wheels for rotating said blade. 15
- 5 12. A propeller comprising a hub having a socket, a blade having a shank rotatable about its own axis in said socket, and means for so rotating said blade shank in either direction, said means comprising a pair of independent toothed gears journaled on said hub, a gear wheel meshing with one of said gears, an idler pinion meshing with said gear wheel and the other of said gears, a worm shaft extending diametrically through said hub and operatively connected to said gear wheel, a pair of worms spaced apart on said shaft and rigidly secured thereto, a pair of oppositely disposed worm wheels meshing therewith, and means operated by said worm wheels for rotating said blade. 20
- 10 25
- In testimony whereof I affix my signature.

SPENCER HEATH,
